UNITED STATES PATENT OFFICE.

LESTER H. DE COSTER, OF JACKSON, MICHIGAN.

WASHING-MACHINE.

1,385,205.

Specification of Letters Patent. Patented July 19, 1921.

Application filed April 15, 1920. Serial No. 374,002.

To all whom it may concern:

Be it known that I, LESTER H. DE COSTER, a citizen of the United States, residing at Jackson, in the county of Jackson and State 5 of Michigan, have invented certain new and useful Improvements in Washing-Machines, of which the following is a specification.

This invention relates to improvements in washing machines.

10 It relates more particularly to washing machines of the so-called vacuum cup or plunger type.

One of the objects of the invention is to provide an improved washing machine of 15 the above type.

Another object is to provide such a washing machine wherein the chance for escaping steam is reduced.

Another object is to provide a washing 20 machine wherein the vacuum cups or pounders coöperate to increase the circulation of the clothes and the cover of the tub may be substantially closed.

Another object is to automatically regulate 25 the amount of reciprocation of the plungers in accordance with the amount or depth of the clothes being washed.

Another object is to provide a washing 30 machine of the type described which will be more durable and may be more readily kept in a sanitary condition.

Other objects and advantages will herein-after appear.

An embodiment of the invention applied 35 to a manually operated machine is illustrated in the accompanying drawings.

In the drawings—

Figure 1 is a plan view of the mechanism.

Fig. 2 is a central section taken on line 40 2—2 of Fig. 1.

Fig. 3 is a central, vertical section taken on line 3—3 of Fig. 1.

Fig. 4 is an enlarged fragment of a part 45 of one of the plunger rods showing parts in section.

Fig. 5 is a similar view of the same at right angles to Fig. 4.

In all of the views the same reference characters are used to indicate similar parts.

50 This invention is shown as embodied in a hand-operated machine, to simplify the disclosure. It will be manifest, of course, that it may be power driven if desired.

The usual round tub 10 may be used in 55 connection with the removable and replaceable machine 11.

The machine has a base plate 12 upon which the machinery is mounted and which serves as a cover for the tub 10. Mounted on the cover 12 are two spaced-apart standards 13 and 14 to provide bearings 15 and 16 for the outer ends of the shafts 17 and 18, respectively. A central bracket 19 provides supports for the inner ends of the spaced-apart shafts 17 and 18. 60

On the shaft 17 is a spur gear pinion 20 and on the shaft 18 is an intermeshing spur gear pinion 21. When the handle 22 is turned to rotate the shaft 18, the shaft 17 is thereby rotated in the opposite direction. 70 The shaft 18 is bent into a crank 23 and the shaft 17 is provided with a crank 24 on the opposite side. A bracket 25 is supported on each of the cranks, and is slidable on its plunger rods 26 and 27, respectively. To 75 prevent the bracket 25 from cramping on its rod, a slidable collar 28 is spaced away and located some distance below the bracket and connected thereto by side rods 29 and 30. The side rods are spaced away from 80 their respective plunger rods 26 and 27 to leave room for an open helical spring 31. The upper end of the spring bears against the lower end of the bracket as at 32, and the lower end is adjustably secured to the 85 rods 26 and 27 as by a collar 33 and set screw 34. The vacuum cups 35 are secured to the lower ends of the rods 26 and 27.

The operation of the device is substantially as follows:— 90

When the handle 22 is rotated clockwise, for example, the cups 35 are moved up and down in the tub. Because of the fact that the cranks are at all times located on opposite sides of a common longitudinal axis, one 95 cup will be ascending while the other is descending.

The plunger rods pass through apertures 36 made through the plate 12, and this opening in each case serves as a pivotal point for the rod. In other words the plungers are pivoted on points substantially in the plane 100 of the cover. The plungers substantially fill the openings in the cover so that the chance for escape of steam and water is reduced to a minimum.

A given point of the cup 35 moves through a path represented by the oval figure shown in dotted lines at 37 and since the longest axis of this oblate path is inclined from a vertical plane, the effect 105 of the cups by their contact with the clothes is to move the clothes around in the tub in a 110

circumferential direction. Since the cranks are rotated in opposite directions the movement of one crank supplements this effect of the other in the circumferential movement 5 of the clothes so that all parts of the clothes are thus successively brought under the influence of the cups. Another effect produced is that the suction of one cup raises the clothes on one side of the tub while the compression effect of the cup on the other side 10 of the tub depresses the clothes. In this way the clothes are given a circumferential movement and an up and down motion.

The springs 31 are compressed, to a 15 greater or less degree, by the down stroke of the cup, to compensate for variation of thickness of the clothes and to give a longer compression dwell of the cup to allow the air more time to escape from the cup through 20 the clothes. The bearing portion 25' of the bracket 25 is cut away at 40 to permit the crank to be inserted, then the cut-away part 41 is replaced and two steel spring snap rings 42, one at each end is placed in grooves 25 made in the parts 25' and 41 to hold the latter in place. By taking the rings 42 out of their grooves the parts may quickly be disassembled. A ring 43 may be secured to the 30 bottom marginal edge of the plate 12 to hold the device on the tub.

The compression springs are located entirely outside of the tub and are consequently protected from the action of the

steam and water. The springs will, in consequence, last longer and may be kept 35 cleaner.

The device may be lifted clear of and removed from the tub and any suitable means may be employed to latch and hold it on the tub. The device is adapted for use 40 with any standard size tub, either wood or metal.

While I have herein disclosed a single embodiment of my invention, it is manifest that numerous changes may be made in the 45 configuration and disposition of the parts within the scope of the appended claim.

Having described my invention, what I claim as new and desire to secure by Letters Patent is:—

In combination with a washing machine having a tub; a substantially closed cover therefor; a crank rotatably supported on the cover; a plunger rod passing through the cover and pivoted in the opening of the 55 cover; a bracket slidable on the rod and pivoted to the crank; a ring spaced away from the bracket, slidable on the rod; side rods on each side of the plunger rod connecting the ring and bracket; a spring wound about 60 the plunger rod and bracket and an axially adjustable collar on the plunger rod at one end of the spring.

In testimony whereof I hereunto subscribe my name.

LESTER H. DE COSTER.
